[57] CLAIM

The ornamental design for a shoe lace cover, as shown and described.

DESCRIPTION

FIG. 1 is a perspective view of the shoe lace cover according to my design;

FIG. 2 is a right side view thereof, the left side being a mirror image;

FIG. 3 is a top view thereof;

FIG. 4 is a front view thereof;

FIG. 5 is a rear view thereof; and,

FIG. 6 is a bottom view thereof.

The broken line showing of the shoe upper and sole in FIG. 1 is for illustrative purposes only and forms no part of the claimed design.
